[57] CLAIM

The ornamental design for a pegboard hook, as shown and described.

DESCRIPTION

FIG. 1 is a side elevational view of a first embodiment of the pegboard hook;

FIG. 2 is a front elevational view of the hook of FIG. 1;

FIG. 3 is a rear elevational view of the hook of FIG. 1;

FIG. 4 is a top plan view of the hook of FIG. 1;

FIG. 5 is a bottom plan view of the hook of FIG. 1;

FIG. 6 is a side elevational view of a second embodiment of the invention;

FIG. 7 is a front elevational view of the second embodiment of the invention;

FIG. 8 is a side elevational view of a third embodiment of the invention; and,

FIG. 9 is a front elevational view of the third embodiment of the invention.

FIG. 1

FIG. 2

FIG. 3

FIG. 4

FIG. 5

FIG.6

FIG.7

FIG.8

FIG.9
